CLAIM

The ornamental design for a earpiece connector for an
earphone, as shown and described.

DESCRIPTION

FIG. 1 is a front elevational view of an earpiece connector
for an earphone showing my new design;
FIG. 2 is a right side elevational view thereof;
FIG. 3 is a left side elevational view thereof;
FIG. 4 is a bottom plan view thereof, rotated 90 degrees
from FIG. 1;
FIG. 5 is a top plan view thereof, rotated 90 degrees
from FIG. 1; and
FIG. 6 is a reduced scale front elevational view thereof,
the broken line showing of the head band, earpieces and
the second connector are for illustrative purposes only.

FIG. 6

FIG. 2

FIG. 1

FIG. 3

FIG. 4

FIG. 5
